UNITED STATES PATENT OFFICE.

MORITZ LIEBSCHNER, OF GUNNERSDORF, NEAR FRANKENBERG, GERMANY, AS-
SIGNOR TO THE FIRM FERD. LIEBSCHNER & SOHN, OF FRANKENBERG I. SA., GER-
MANY.

PICKER FOR LOOMS.

Application filed April 5, 1927, Serial No. 181,208, and in Germany November 1, 1926.

The pickers, commonly used in connection with cloth- silk- and other looms present the inconvenience that in the picker-head a plug is fixed by metal rivets so that, when the 5 plug has been worn so that the iron rivet strikes onto the pointed end of the shuttle, the picker cannot be used any more as the shuttle would be damaged so that the warps break.

10 To avoid this inconvenience it has been proposed to make the pickers from a piece of leather and to produce the head by upsetting.

According to the invention the plug is fitted with a leather edge engaging with an 15 incision in the leather envelope and held in this manner. Leather rivets are further driven in to prevent distortion. The picker head is made entirely of leather so that it runs silently in the shuttle box while the 20 commonly used pickers with metal rivets caused shocks owing to the rivet heads striking on the shuttle box.

In order to make the picker, which is more durable at the head than the commonly used 25 pickers, more durable also at the point on which the batting arm acts, i. e. at the point of fixation where premature tearing of the pickers happens frequently as the dressed buffalo-hide is often brittle, an insertion of 30 mineral tanned leather is arranged in the fixing part wound around the spindle.

A picker improved according to the inven-

tion is shown, by way of example, in the accompanying drawing, in Fig. 1 in side elevation, the head being partly broken away. 35 Fig. 2 shows an end elevation. Fig. 3 shows the plug head alone in front elevation.

The plug 1 is held, as shown in Fig. 1, in the picker head 2 by an enlargement 3, preferably of leather, and engaging with a cavity 4 in the material of the head 2. Two leather rivets 5 serve to prevent distortion of the plug 1. In the fixation part 6 an insertion 7 of mineral tanned leather is arranged, in order to improve the durability of this part. The 45 insertion 7 surrounds the hole 8 designed to receive the spindle.

I claim:-

A picker for looms consisting of a main part of several layers of leather having a 50 cavity and a ring-shaped groove, an insertion plug made of a strip of leather wound up inserted in said cavity of said main part and having a wide low rim inserted into the ring-shaped groove of said main part, and of 55 several bolts made of wound up strips of leather and extending transversely through said main part and insertion plug fixing said insertion plug in said main part so that the striking power of the picker is transmitted 60 from the shuttle point to the strap only by connecting elements of leather.

In testimony whereof I affix my signature.

MORITZ LIEBSCHNER.
